UNITED STATES PATENT OFFICE.

AMOS J. STETLER, OF WEST POINT, PENNSYLVANIA.

CUFF-BUTTON.

1,062,049.

Specification of Letters Patent.

Patented May 20, 1913.

Application filed August 14, 1912. Serial No. 714,969.

To all whom it may concern:

Be it known that I, AMOS J. STETLER, a citizen of the United States, residing at West Point, in the county of Montgomery and State of Pennsylvania, have invented 5 certain new and useful Improvements in Cuff-Buttons, of which the following is a specification.

My invention relates to improvements in 10 cuff buttons, the object of the invention being to provide a cuff button which can be attached to the lining of a coat sleeve and a cuff secured thereon, so that when the wearer takes off his coat, the cuffs will remain 15 cured to the sleeves.

A further object is to provide a button of 20 this character made up of several parts, the sleeve lining being hooked over one part and prevented from accidentally coming 25 off by a plate, the latter held over the hooked member by a removable head.

A further object is to provide a cuff button which can be easily attached to and detached from a coat sleeve in a short space of 25 time, which will be cheap to manufacture and will perform the functions for which it is intended.

In the accompanying drawings, Figure 1, 30 is an exaggerated view in side elevation showing my improvement. Fig. 2, is a view in vertical section and showing a portion of a sleeve lining and cuff. Fig. 3, is a bottom plan view.

1 represents a base plate having an opening 2 therein through which a pin 3 projects. This pin 3 has a screw threaded portion 4 on one side of the plate 1, and extends through the opening 2. It is bent at right angles to the threaded portion 4 as 35 shown at 5, and lies parallel with the under face of plate 1. This portion 5 is bent back upon itself forming a straight member 6, which extends across the bottom of plate 1, and has a hooked end 7 adapted to catch in 40 a sleeve lining 8, and projecting into a slot 9 in plate 1. This hooked end is at an approximate right angle to member 6 so that the hooked end and the threaded portion extend in the same direction.

50 A head 10 is screwed onto the threaded portion 4 of pin 3, and has a reduced shank 11 to receive the cuff 12. This head 10 is

beveled outwardly from its outer to its inner end, and a shoulder 13 is formed at the juncture of the head and the shank so there 55 is no possibility of the cuff accidentally coming off.

The plate 1 is provided with several slots 9 as seen in Fig. 3, to receive the hooked end 7 and the spokes 14 between the slots 60 prevent the plate from revolving and wearing on the sleeve lining and the cuffs. By bending the pin 3 so that it will project radially on both sides of the central opening as clearly seen, any possibility of the pin 65 getting at an angle to plate 1, and the two coming apart, is overcome.

In assembling the device the hooked end 7 and part of the member 6 are caught in the lining of a coat sleeve as seen in Fig. 2. 70 The plate 1 is then positioned over the same with the end 7 projecting into one of the slots 9 and the threaded portion 4 through the central opening 2. Head 10 is then screwed on the threaded portion 4 and will 75 press the plate 1 down on member 6 and the portion 5, clamping the lining between the plate and member 6. The cuff is then secured over the head 10 onto shank 11 and in this manner is securely buttoned to the 80 coat sleeve, so that the cuffs are removed whenever the coat is taken off.

Various slight changes might be made in the general form and arrangement of parts described without departing from my invention, and hence I do not limit myself to the precise details set forth, but consider myself at liberty to make such changes and alterations as fairly fall within the spirit and scope of the appended claim. 90

Having thus described my invention what I claim as new and desire to secure by Letters Patent is:

A device of the character described, comprising a base plate having a central opening therein, a pin having a threaded end and projecting through the opening in the plate, said pin then bent at right angles and extending radially across the bottom of the plate, said pin then bent upon itself and 95 extending diametrically across the bottom of the plate forming a clamping head, a hook on the end of the pin adapted to be projected through a support, said plate hav- 100

ing a series of slots therein, in any one of which the hooked end may project, and a head screwed on the threaded portion of the pin, securing the parts together and 5 clamping the support between the clamping head and the base plate, substantially as described.

In testimony whereof I have signed my name to this specification in the presence of two subscribing witnesses.

AMOS J. STETLER.
